(57) **CLAIM**

The ornamental design for a valve handle operation jig as shown and described.

DESCRIPTION

1.1 : Front

1.2 : Back

1.3 : Top

1.4 : Bottom

1.5 : Left

1.6 : Right

1.7 : Cross sectional view thereof along line A-A in front view

1.8 : End view thereof along line B-B in top view

A valve handle operation jig that allows a valve handle to be operated using a wrench; the part for which a design registration is sought is specified, including a cross-sectional view and an end view.
